(57) **CLAIM**

The ornamental design for a digital piano and triple pedal set as shown and described.

DESCRIPTION

FIG. 1 is a top perspective view of a digital piano and triple pedal set showing my new design; the triple pedal shown removed for ease of illustration;

FIG. 2 is a bottom perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of the portion taken at line-9 in FIG. 1;

FIG. 10 is an enlarged view of the portion taken at line-10 in FIG. 1;

FIG. 11 is an enlarged view of the portion taken at line-11 in FIG. 1;

FIG. 12 is a perspective view of a digital piano and triple pedal set; the digital piano shown removed for ease of illustration;

FIG. 13 is a bottom perspective view thereof;

FIG. 14 is a front view thereof;

FIG. 15 is a back view thereof;

FIG. 16 is a left side view thereof;

FIG. 17 is a right side view thereof;

FIG. 18 is a top plan view thereof;

FIG. 19 is a bottom plan view thereof; and,

FIG. 20 is a perspective view of the digital piano and triple pedal set.

The broken lines represent the portions of the digital piano and triple pedal set that form no part of the claimed design.
